UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC-LAMP SOCKET.

1,180,997.

Specification of Letters Patent. Patented Apr. 25, 1916.

Application filed July 15, 1915. Serial No. 40,110.

To all whom it may concern:

Be it known that I, FREDERIC P. GATES, a citizen of the United States of America, and residing at Hartford, in the county of Hartford and State of Connecticut, have invented a certain new and Improved Electric-Lamp Socket, of which the following is a specification.

My invention relates to electric lamp sockets and particularly to porcelain sockets, the object of my invention being to provide a socket of improved construction having the features of novelty hereinafter described and shown in the accompanying drawing in which—

Figure 1 is a side elevation of a socket in which my invention is illustratively embodied; Fig. 2 is an elevation partially in section of the switch spindle and thumb piece; and Fig. 3 is an end elevation of the latter.

In the form here shown the present socket comprises an insulating casing 10 of porcelain or the like carrying wire terminals and switch mechanism (not shown) within the upper portion thereof which may be operated by the porcelain thumb piece 11 operatively engaging the switch spindle 12. The circuit is as usual led to the lamp receptacle contacts, of which only the screw shell 13 is here shown. The porcelain casing is extended below the latter a considerable distance and is flared out sharply. The flared portion *x* of the skirt serves as a reflector which deflects downward the rays of light normally upwardly directed from the lamp. The efficiency of the latter is thus increased.

A second feature of improvement in the present construction resides in the manner in which the porcelain thumb piece 11 is secured to the spindle 12. It has heretofore been customary to split the end of the spindle and spread the opposite sides of the split end in a well in the outer end of the thumb piece, by a staking operation. This method of attaching the thumb piece not only adds the expense of a second operation upon the spindle after the thumb piece is assembled thereon, in order to accomplish the staking operation, but it is also attended by a very heavy percentage of breakage which seems to be unavoidable in the practical accomplishment of the staking operation. The staking operation thus performed secures the thumb piece at the outer end against

a shoulder formed upon the spindle adjacent the inner end of the thumb piece so that there is practically no longitudinal play of the thumb piece on the spindle. I have now modified the method of attachment by 60 striking wings 13 from the end of the spindle which engage in a cross slot 14 opening to the well 15 in the outer end of the thumb piece. This affords an engagement between the parts serving to prevent their relative 65 rotary displacement and enabling the operator to actuate the switch mechanism by the rotation of the thumb piece through the engagement of the latter with the wings 13 of the spindle. To prevent the longitudinal 70 displacement of the thumb piece on the spindle to a sufficient extent to permit the wings to escape from the well 15, I have made the spindle of such length that in the assembled position thereof in the socket 75 body only a very slight longitudinal play of the thumb piece on the spindle is permitted before the shank 16 thereof abuts against the side of the porcelain body. This longitudinal displacement is so slight 80 that the wings 13 are retained at all times within the well 15 and cross slots 14, and the operative engagement between the thumb piece and spindle thus insured.

To assemble the parts it is merely necessary to pass the spindle with the wings 13 already formed thereon through the thumb piece 11 in a direction to seat the wings in the cross slot 14 with the length of the spindle projecting through the shank 16. 90 The customary staking operations which are thereafter performed upon the spindle in order to engage it with the switch frame and circuit breaker may be accomplished without danger of injury to the thumb piece. 95

Various modifications of the two features of the construction hereinabove described will readily suggest themselves to those skilled in the art without departing from what I claim as my invention. 100

I claim as my invention:

1. An electric lamp socket comprising a porcelain casing, a switch spindle projecting therefrom, a porcelain thumb piece pierced by said spindle, and having a non-circular well in its outer end, together with a non-circular abutment on the spindle within said well engaging said thumb piece to prevent relative rotary displacement of the latter with relation to the spindle and confining 110

said thumb piece so closely between said abutment and the casing as to prevent the escape of said abutment from the well in the thumb piece through longitudinal movement of the latter on the switch spindle.

2. An electric lamp socket comprising a porcelain casing, a switch spindle projecting therefrom, a porcelain thumb piece for operating said spindle, said thumb piece being 10 pierced by an aperture adapted to receive the switch spindle and having a well of non-circular contour communicating with said piercing and opening to the opposite end of the thumb piece to receive a non-circular 15 head on the end of the spindle whereby the thumb piece may be assembled upon the

spindle by passing the latter through the well and piercing until the head of the spindle rests in the bottom of said non-circular well, in combination with stakings 20 on said spindle engaging within the lamp socket to prevent the escape of the thumb piece from the spindle in the assembled position of the parts.

In testimony whereof I have signed my 25 name to this specification, in the presence of two subscribing witnesses.

FREDERIC P. GATES.
